UNITED STATES PATENT OFFICE.

AMBROSE G. FELL, OF NEW YORK, N. Y., ASSIGNOR TO WILLIAM H. SMITH,
OF URBANA, ILLINOIS.

BLEACHING CANE-JUICE, SIRUP, AND OTHER MATERIALS WITH SULPHURIC ACID, &c.

SPECIFICATION forming part of Letters Patent No. 254,471, dated March 7, 1882.

Application filed October 3, 1881. (No specimens.)

To all whom it may concern:

Be it known that I, AMBROSE G. FELL, of New York city, in the county and State of New York, have invented a new and useful Improvement in Bleaching Cane-Juice, Sirups, and other Materials with Sulphurous Acid, and in the manufacture of the latter therefor, and for other purposes, which improvement is fully set forth in the following specification.

This invention has reference more particularly to the clarifying or bleaching of cane-juice and other saccharine solutions or sirups by means of sulphurous acid, and has for its object to secure a more efficient action of the gas, and also to overcome certain difficulties attending the manufacture and application due to its corrosive nature.

Various methods have been heretofore devised for subjecting the sirup to the action of the sulphurous acid and for generating the latter, but ordinarily the sirup is placed in an open tank six to eight feet in depth, and the sulphurous-acid gas obtained—say from burning sulphur or compound containing the same—is forced through the liquid by means of a pump. The difficulties attending this treatment are that the sulphurous-acid gas passing rapidly through the liquid remains in contact therewith for too short a time, and lacks that force of contact and intimacy of admixture necessary for efficient action and the production of the best results; that a large quantity of the gas is required for obtaining even inferior results, and that the valves and other parts of the pump are rapidly corroded.

It is deemed unnecessary here to recite the different methods devised for subjecting sirup and other bodies to sulphurous-acid gas. Suf-
fice it to say that they are attended in a great-
er or less degree with the disadvantages indi-
cated. Sulphurous acid, therefore, is only em-
ployed to remove a small amount of color from
a comparatively light or thin solution, since to
remove the color from a heavy dark sirup
would require too much time and the con-
sumption of too large a quantity of sulphur.

In some cases it is desired to transport the sulphurous acid from the place of manufacture to where it is to be used. Heretofore the gas

has been forced into vessels by means of pumps, 50 and in order to avoid the corrosion and wear upon the latter it has been necessary to render the gas anhydrous by removal of the water vapor, thus increasing the labor and expense.

In the present invention the difficulties and disadvantages referred to are overcome or avoided. The cane-juice or sirup is subjected to the action of the sulphurous acid in close vessels under high pressure and is intimately mixed and held in contact therewith, so that 60 even with dark-colored sirup a comparatively short time, with small expenditure of sulphur, is required satisfactorily to remove the coloring-matter. The pressure in the treating-vessel or in a storage-vessel, when the sulphurous acid 65 is to be kept in supply or transported, is obtained without contact of the gas with a pump, 70 by forcing the air into the chamber in which sulphur is burning, so that air is supplied thereto under pressure, and the gas as it escapes is compressed to the degree required for efficient operation upon the sirup or for storage. All the operations being performed in close vessels, there is no escape of gas to annoy the workmen or to be a source of waste to 75 the manufacturer.

The following description will enable those skilled in the art to which the invention relates to make and use the same.

The sulphur or its compound is placed in a 80 close air-tight vessel capable of sustaining a high pressure. It is preferred to have this vessel cylindrical in form, and provided with trunnions on which to revolve. The sulphur is ignited in this vessel, and air or oxygen to 85 support the combustion is supplied by means of a pipe from an air-compressor leading into the combustion-chamber. By this air or oxygen the combustion of the sulphur and the consequent formation of sulphurous gas is 90 maintained at any desired pressure. The combustion vessel or chamber is provided with an outlet-pipe to conduct the product of combustion (sulphurous-acid gas) to wherever desired for use or storage. The inlet and outlet are 95 formed in the trunnions.

The reason for preferring a cylindrical rotat-
ing vessel in which to burn the sulphur or its

compound is that as the vessel turns on its trunnions the melted and burning sulphur adheres to its whole interior surface, thus exposing a larger and thinner area of sulphur under combustion than is practicable in a stationary vessel, and the thinner the area of sulphur under combustion the less likelihood of volatilizing the sulphur without its previous combination with the oxygen, which is necessary to the formation of sulphurous acid. In a stationary vessel the sulphur melts by the heat of the combustion, and as that combustion is confined to the surface of the melted sulphur, the bulk of the sulphur being therefore in a melted condition, but not under combustion, is apt to volatilize in the form of flowers of sulphur. Increasing the combustion-area by revolving the vessel or chamber in which the combustion takes place not only lessens the proportion of volatilized sulphur produced, but also greatly increases the production of sulphurous acid by exposing to the action of the oxygen of the air a larger area of sulphur.

After the formation of the sulphurous-acid gas, and previous to its introduction into the bleaching-chambers or storage-reservoirs, it can be cooled and purified by any of the various means usually employed for such purposes and well understood.

The bleaching-chamber for treating sirups may be an upright cylindrical vessel of about ten by four and one-half feet, made of cast-iron and provided with proper inlets and outlets, a safety-valve, a glass gage, through which the bleaching effect can be watched as it advances, and also a stirrer similar in style to a screw-propeller. The stirrer is carried by an upright shaft inclosed in a stuffing-box at the point of entry into said bleaching-vessel. This vessel is nearly filled with cane-sirup of an inferior grade, dark in color, and of any desired gravity. The stirrer is now put in motion and the supply of sulphurous acid from the combustion-chamber is turned on and allowed to flow into the bleacher. The safety-valve is raised, or, if the sirup foams in the bleacher, the valve is set at a few pounds only until the escape of sulphurous acid therefrom indicates that all the atmospheric air has been displaced and driven out. It is then closed and weighted to fifty pounds, more or less. The sulphurous acid is allowed to accumulate until that pressure is reached, when the supply of gas is shut off, and the agitation continued without the addition of more gas for forty-five minutes, or longer, or until the desired effect is obtained and the operation complete. The pressure remaining in the bleacher is utilized to force the sirup out of a bottom outlet and pipe into a reception-tank placed above the bleacher, from whence it can be put through animal-coal, or otherwise treated to remove the sulphurous acid.

The pressure in the bleaching-chamber is produced direct from the vessel in which the combustion of the sulphur takes place, and that pressure of acid-gas therein contained is continually renewed and maintained by means

of fresh air supplied by the compressor, which, bringing into combustion further amounts of sulphur, insures the continued formation of 70 fresh supplies of sulphurous-acid gas at any pressure within the capacity of an air compressor or pump, or other device to produce.

As to the style of air-compressor to be employed it is immaterial, as the gas does not 75 come in contact therewith, and no consequent corrosion or wear occurs. Any of the well-known air-pumps will answer, and will last as long as when employed for any other purpose.

When it is not intended to use the sulphurous gas immediately, or if it is intended for use elsewhere, then the pressure in the combustion chamber is employed to force the sulphurous acid into close and strong storage-vessels, similar to those employed for storage of 85 carbonic acid, as supplied to the soda-water trade, and in these vessels it can be conveyed to any distance, to be used in any manner and for any purpose desired. The sulphurous acid can be liquefied in these vessels, which can be 90 cooled to aid the liquefaction.

From a reservoir of the compressed gas connection may be made with a bleaching-chamber, such as described.

In compressing the gas into storage-vessels 95 it is not essential that the gas should be dried; but this could be done, if desired, by passing it through or over sulphuric acid, chloride of sodium, or any hygroscopic material contained in suitable apparatus, as understood in the arts. 100

Although the invention, as already described, particularly relates to the clarification or bleaching of cane-juice or other sirups or saccharine solutions, it is applicable in part, at least, to other purposes. For example, liquids 105 other than cane-juice, or even solid substances, could be placed in the bleaching-chamber and treated with the sulphurous-acid gas under pressure; but with solid materials a stirrer for agitating them would not ordinarily be required. Analogous means, however, for bringing the sulphurous acid into contact with every part of said material could be used.

The pressure of the sulphurous acid in the bleaching or treating chamber can of course 115 be made less or greater, as required, or as deemed expedient.

The methods before described could be carried out with a stationary combustion-chamber or with any suitable apparatus, although 120 that indicated is deemed most advantageous.

The sulphurous acid stored in reservoirs could of course be used for any purpose to which it might be adapted.

Having now fully described my said invention and the manner of carrying the same into effect, what I claim is—

1. The method of treating cane-juice, sirups, or other materials, solid or liquid, with sulphurous acid by subjecting the same to the action of the sulphurous acid under pressure, substantially as described.

2. The method of bleaching cane-juice, sirups, or other materials, liquid or solid, by sub-

jecting the same in a close vessel to the action of compressed sulphurous acid under a high degree of pressure, and using agitation to bring the acid-gas in contact with all parts of said cane-juice or other materials, substantially as described.

3. The method of obtaining compressed sulphurous acid for storage or for immediate use by burning sulphur, or a compound of the same, in a close vessel, forcing compressed air or oxygen into said vessel to support combustion, and conveying the products (sulphurous-acid gas) into a close vessel, wherein the pressure is allowed to accumulate to the desired degree, substantially as described.

4. The method of producing sulphurous acid by burning sulphur, or a compound thereof, in compressed air or oxygen in a revolving cylindrical vessel or chamber, so as to expose to the oxidizing action a large and thin area of sulphur, substantially as described.

5. The improvement in treating cane-juice or other materials, solid or liquid, with sulphurous acid, consisting in burning sulphur, or com-

pound thereof, in compressed air or oxygen, so as to obtain sulphurous acid under pressure, and subjecting the cane-juice or other material to the action of the compressed sulphurous acid, substantially as described.

6. The improvement in clarifying or bleaching cane-juice or other sirup, consisting in treating the dark-colored sirup with sulphurous acid under pressure, substantially as described.

7. The method of producing sulphurous acid for use in the arts by burning sulphur, or a compound thereof, in compressed air or oxygen in a vessel or chamber, and using the pressure in the chamber to force the sulphurous acid, whether gaseous or liquid, into close and strong storage-vessels, substantially as described.

In testimony whereof I have signed this specification in the presence of two subscribing witnesses.

A. G. FELL.

Witnesses:

JOHN McCCLURE,
J. TALMAN WATERS, Jr.

It is hereby certified that in Letters Patent No. 254,471, granted March 7, 1882, upon the application of Ambrose G. Fell, of New York, New York, the title in the grant of said Letters Patent and at the head of the printed specification attached to and forming a part thereof, was erroneously written and printed improvement in "Bleaching Cane Juice, Sirup, and other Materials, with Sulphuric Acid, &c." instead of "Bleaching Cane Juice, Sirup, and other Materials, with Sulphurous Acid, &c.;" that the correct title of said invention is improvement in "Bleaching Cane Juice, Sirup, and other Materials, with Sulphurous Acid, &c.;" that the proper corrections have been made in the files and records pertaining to the case in the Patent Office, and are hereby made in said Letters Patent.

Signed, countersigned and sealed this 21st day of March, A. D. 1882.

[SEAL.]

A. BELL,
Acting Secretary of the Interior.
